UNITED STATES PATENT OFFICE.

ROBERT E. EINSTEIN, OF ST. LOUIS, MISSOURI, ASSIGNOR TO ST. LOUIS FROG & SWITCH COMPANY, OF ST. LOUIS, MISSOURI, A CORPORATION OF MISSOURI.

SPLIT SWITCH.

Application filed October 29, 1923. Serial No. 671,452.

To all whom it may concern:

Be it known that I, ROBERT E. EINSTEIN, a citizen of the United States, residing at St. Louis, Missouri, have invented a certain new and useful Improvement in Split Switches, of which the following is a full, clear, and exact description, such as will enable others skilled in the art to which it appertains to make and use the same.

10 This invention relates to split switches, and particularly to the means used in such railway track structures for supporting the laterally-movable switch point and the stationary track rail with which said switch 15 point co-operates and for securely holding said rail in position to maintain the proper gauge of the track.

One object of my invention is to provide a means of the character referred to that is 20 composed of a standard or universal slide plate capable of being used with stock rails of different weights or sizes, and an adjustable variable element that co-operates with a rail brace arranged on the outer side of the 25 stock rail to hold the inner edge of the base flange of said rail in engagement with a shoulder or abutment on said slide plate. Due to the fact that the slide plate can be used with rails of various weights having 30 base flanges of different widths, considerable saving in the cost of manufacture and maintenance of such structures is effected by overcoming the necessity of making and keeping on hand a large number of different sized 35 slide plates. Moreover, a standard or universal slide plate makes it possible to change the size of the rails of a split switch,—for example, from a heavy to a light weight rail, or vice versa, without the necessity of re- 40 moving the slide plates of the switch and replacing them with other plates designed for use with the particular size of rail being installed.

Another object of my invention is to provide a novel means for supporting and holding the stock rail of a split switch which is 45 of such design that it securely holds said rail to gauge and effectively takes up the vertical and lateral thrusts exerted on said rail in a 50 direction tending to tip it sidewise.

And still another object of my invention is to provide a split switch in which the slide plate and the means that maintains the stock rail in operative position on said slide plate 55 are of such design that slight wear and ir-

regularities in size of the co-operating parts of the structure can be compensated for by adjusting one element of the structure. Other objects and desirable features of my invention will be hereinafter pointed out. 60

Figure 1 of the drawings is a transverse sectional view of a split switch constructed in accordance with my invention.

Figure 2 is a top plan view of the parts illustrated in Figure 1, the stock rail and 65 movable point being shown in horizontal section; and

Figure 3 is an end view of the slide plate, showing the rail brace in side elevation.

Referring to the drawings which illustrate 70 the preferred form of my invention, A designates the stock rail or stationary track rail of a split switch, B designates the movable point that is adapted to be moved laterally towards and away from the rail A, and C 75 designates a member, commonly referred to as a "slide plate" that supports the stock rail A and movable point B. The slide plate C is adapted to be spiked or otherwise secured to the ties of the track, and it is provided with a flat, horizontally-disposed bearing surface 1 on which the switch point B slides. It is also provided with a depressed seat for the stock rail A formed by a flat 80 surface 2 on which the base flange 3 of said rail rests and vertically-disposed shoulders 4 and 5 at the ends of the rail flange supporting surface 2. The shoulder 4 forms an abutment against which the inner edge of the base flange 3 of the rail A is held and the 85 shoulder 5 forms an abutment that co-operates with a filler block D which is arranged between said shoulder and the outer edge of the base flange 3 of the rail A. As shown in Figure 1, the distance between the 90 shoulders 4 and 5 is considerably greater than the width of the base flange 3 of the stock rail, thereby enabling the slide plate C to be used with rails of different weights by 95 substituting different sized filler blocks D. 100

It will thus be seen that in my improved split switch the seat for the base flange 3 of the stock rail comprises an integral shoulder or abutment 4 on the slide plate that bears against the inner edge of the 105 base flange of the stock rail, and a variable element, namely, the filler block D which is interposed between the outer edge of the base flange of the stock rail and a separate shoulder or abutment 5 on the slide plate. 110

The stock rail A is retained in operative position on the slide plate C by means of a rail brace E arranged on the outer side of said rail and constructed in such a way that it effectively resists the strains exerted on said rail in a direction tending to tilt it sidewise. As shown in the drawings, the brace E is constructed in such a way that it will bear against the underside of the head 10 of the rail A and the top side of the base flange 3 of said rail and it is provided with a base portion 6 that partially overlaps the filler block D. Said rail brace is held tightly against the rail A by a wedge-shaped, integral portion 7 on the top side of the filler block D that is interposed between the abutment 5 on the slide plate C and the outer edge of the base piece 6 of the brace E. The outer edge of said wedge-shaped portion 7 which bears against the abutment 5 is parallel to the rail A, but the inner edge of said wedge-shaped portion and the edge of the base piece 6 of the brace E against which it bears are both inclined slightly 20 relatively to the rail A, as shown in Figure 2. Consequently, by moving the filler block D longitudinally of the rail A and transversely of the slide plate in one direction, the wedge-shaped portion 7 on said block 30 will co-operate with the inclined edge of the base piece 6 of the rail brace E to force said brace inwardly towards the rail A, and cause said brace to exert sidewise pressure on said rail in a direction to force the inner edge of the base flange 3 of the rail tightly 35 against the shoulder 4 on the slide plate.

After the filler block D has been adjusted to force the inner edge of the base flange of the rail A into snug engagement with the abutment 4 on the slide plate 1, said filler block is locked in adjusted position, preferably by means of a retaining element F positioned between guides 8 on the brace E and arranged in overlapping relation with the wedge-shaped portion 7 of the filler block. The retaining element F is provided on its underside with serrations that interlock with serrations on the top side of the wedge-shaped portion 7 of the filler block and a bolt 9 is provided for drawing said retaining element F downwardly towards the slide plate. The bolt 9 passes upwardly through the slide plate C, through the filler block D and through the retaining element F, the opening in the filler block through which said bolt passes consisting of an elongated slot, as shown in broken lines in Figure 2, so as to provide for the movement of the filler block transversely of the slide plate during the operation of adjusting said filler block. It will, of course, be understood that it is necessary to loosen the nut on the bolt 9 sufficiently to permit the retaining element F to be disengaged from the wedge-shaped portion 7 of the filler

block D before said filler block can be moved transversely of the slide plate C so as to force the inner edge of the base flange of the rail A against the shoulder 4 on the slide plate.

By constructing a split switch in the manner above described I am able to use a standard slide plate with rails of various weights, thereby materially reducing the cost of manufacture and maintenance of such structures, and I overcome the necessity of taking up the slide plates of a switch whose rails are being replaced by rails of a different weight. Moreover, such a construction makes it possible to maintain the inner edge of the base flange of the stock rail in snug engagement with a shoulder provided for same on the slide plate, because a slight adjustment of the filler block D transversely of the slide plate shifts the co-operating parts of the structure relatively to each other sufficiently to compensate for slight wear or irregularities in the dimensions of said parts.

Having thus described my invention, what I claim as new and desire to secure by Letters Patent is:

1. A split switch, comprising a slide plate provided with a depressed seat that has an abutment at one end of same, a movable switch point slidingly mounted on said plate, a stationary track rail mounted on said seat with the inner end of its base flange bearing against said abutment, a brace arranged on the outer side of said rail, a second abutment on said slide plate at the opposite end of said seat, and an adjustable means interposed between said brace and the second abutment on said slide plate for holding said brace in engagement with said rail and for pressing the inner edge of the base flange of said rail against the abutment on the slide plate first referred to.

2. In a split switch, a slide plate provided with a depressed seat having abutments at the ends of same, a track rail positioned in said seat and arranged with the inner edge of its base flange in engagement with one of said abutments, a brace arranged on the outer side of said rail, and an adjustable element arranged between said brace and the other abutment on said slide plate and adapted to be moved in one direction to force said brace into snug engagement with said rail and to force the base flange of said rail into engagement with its cooperating abutment.

3. A split switch, comprising a slide plate, a laterally-movable switch point and a stock rail mounted on said slide plate, an abutment on said slide plate against which the inner edge of the base flange of said rail bears, an independent abutment on said slide plate spaced away from the outer edge of the base flange of said rail, a filler block interposed

between said independent abutment and the flange of the rail, a rail brace arranged on the outer side of the rail, and means on said filler block that co-operates with said rail brace to exert pressure on same in a direction tending to hold the inner edge of the base flange of the rail in snug engagement with the abutment provided for same on the slide plate.

10 4. In a split switch, a slide plate provided with two abutments arranged in spaced relation, a track rail mounted on said plate with the inner edge of its base flange bearing against one of said abutments, a filler block 15 on said slide plate arranged between the other abutment and the outer edge of the base flange of the rail, a rail brace arranged on the outer side of the rail in overlapping relation with said filler block, and means 20 whereby the adjustment of said filler block transversely of the slide plate forces the brace into snug engagement with the rail and forces the inner edge of the base flange of the rail into snug engagement with the 25 abutment provided for same on the slide plate.

5. In a split switch, a slide plate provided with two abutments arranged in spaced relation, a track rail mounted on said plate 30 with the inner edge of its base flange bearing against one of said abutments, a filler block on said slide plate arranged between the other abutment and the outer edge of the base flange of the rail, a rail brace arranged 35 on the outer side of the rail in overlapping relation with said filler block, and a wedge-shaped portion on the filler block arranged in sliding engagement with an inclined surface on said rail brace, for the purpose described.

40 6. In a split switch, a slide plate provided with a depressed seat and two abutments arranged in spaced relation, a track rail

mounted in said seat with the inner edge of its base flange bearing against one of said abutments, a filler block interposed between 45 the other abutment on said plate and the outer edge of the base flange of the rail, a rail brace arranged on the outer side of the rail and provided with a base piece that laps over said filler block, a wedge-shaped portion 50 on the top side of said filler block that bears against an inclined surface on the base piece of said brace thus causing said brace to clamp the inner edge of the base flange of the rail against its co-operating abutment 55 when the filler block is adjusted in one direction, and means for retaining said filler block in adjusted position.

7. In a split switch, a slide plate provided with two abutments arranged in spaced relation, a track rail mounted on said plate with the inner edge of its base flange bearing against one of said abutments, a filler block interposed between the other abutment on 60 said plate and the outer edge of the base 65 flange of the rail, a rail brace arranged on the outer side of the rail and provided with a base piece that laps over said filler block, a wedge-shaped portion on the top side of 70 said filler block that co-operates with the base piece of said brace to clamp the brace against the rail and clamp the inner edge of the base flange of the rail against its co-operating abutment when the filler block is 75 adjusted in one direction, a retaining element arranged between guides on the base piece of the brace and provided on its underside with serrations that co-operate with serrations in the top face of the wedge-shaped portion of the filler block, and a bolt or the like that 80 passes upwardly through the slide plate, filler block and retaining element.

ROBERT E. EINSTEIN.
